United States Patent Office

Des. 196,062
Patented Aug. 20, 1963

196,062

CAN PUNCH

Raymond W. Barton, % Mead Johnson & Co.,
Evansville, Ind.

Filed Dec. 21, 1962, Ser. No. 72,922

Term of patent 14 years

(Cl. D44—29)

I claim:

The ornamental design for a can punch, as shown and described.
